UNITED STATES PATENT OFFICE.

GEORGE H. PAULUS, OF DETROIT, MICHIGAN.

SHARPENING DEVICE FOR LAWN-MOWERS AND OTHER ARTICLES.

No 831,183.

Specification of Letters Patent.

Patented Sept. 18, 1906.

Application filed December 21, 1905. Serial No. 292,819.

To all whom it may concern:

Be it known that I, GEORGE H. PAULUS, a citizen of the United States, residing at Detroit, county of Wayne, State of Michigan, have invented a certain new and useful Improvement in Sharpening Devices for Lawn Mowers and other Articles, of which the following is a specification, reference being had to the accompanying drawings, which form a part of this specification.

My invention has for its object a sharpening device for lawn-mowers and other articles; and it consists of the structure herein-after described and claimed, and illustrated in the accompanying drawings, in which—

Figure 1 is a view in cross-section, illustrating my device as applied to the edge of a cutter-bar of a lawn-mower. Fig. 2 is a detail view of the sharpening device in perspective. Fig. 3 is a cross-section through the sharpening device. Fig. 4 is a view in end elevation, showing the sharpening device in place upon the edge of the cutter-bar of a lawn-mower.

The desirability of a simple, economical, and efficient sharpening device for the revolving cutter-blades of a lawn-mower is obvious, and whereby the revolving cutter-blades may be sharpened evenly and uniformly throughout the entire length of such blades, so as to insure their efficient operation.

Heretofore where the cutting-blades of a lawn-mower have been sharpened by a file there has been great liability of filing away the blade more at one extremity than another or at one point more than another, while also different cutter-blades are unevenly sharpened, no two blades being sharpened exactly alike, resulting in the speedy destruction of the machine or rendering the machine useless for further work while only the cutter-blades may be damaged, where-as if the cutter-blades have been sharpened uniformly and all alike much more wear could have been obtained from the machine. Practically the same is true where the cutter-blades have been sharpened upon a revolving grinding-wheel. Each blade being sharpened separately by itself is liable, the same as where a file is applied, to be sharpened unevenly from end to end and the different blades are also sharpened unevenly, often necessitating a throwing of the machine into the junk-pile before its other parts have been much damaged.

My present invention is designed to avert these difficulties in a simple and efficient manner and to provide means whereby any operator may readily sharpen the revolving cutter-blades of his lawn-mower, and whereby the blades will be evenly sharpened from end to end, and whereby also the different blades will be uniformly sharpened alike, thereby giving much greater length of life to the machine, increasing its efficiency and length of service.

To these ends my invention consists, essentially, of a sharpener which may be readily attached to the stationary cutter-blade of a lawn-mower.

My improved sharpener is constructed, essentially, of a body *a*, of any suitable material, hard wood being preferable, the same having been thoroughly seasoned, said body being provided with a kerf or slot, (indicated at *b*.) the kerf being of sufficient width and depth to allow the body to be applied to the edge of the stationary cutter-blade of the mower, the edge of the blade entering said kerf. The body thus presents two surfaces, the one above and the other below the plane of the cutter-blade, the two surfaces of the sharpening device being preferably coated with emery or other suitable abrading or grinding substances, (indicated at *c*.)

While I do not limit myself solely to having the two surfaces of the body of the sharpening device form abrading or grinding surfaces, yet it will be economical and preferable to have both the upper and lower surfaces of the body provided with abrading-surfaces, as it will be readily apparent that the sharpening device may thus be readily changed from end to end, so as to bring one surface after another into position upon the edge of the cutter-blade to sharpen the revolving cutter-blades. The body of the sharpening device will be of such thickness as to set above the edge of the blade only a required distance for the revolving cutter-blades to contact therewith in their revolution.

It will be evident that in the revolution of the blades to be sharpened the force is toward the edge of the stationary cutter-blade, so that as the revolving cutter-blades contact with the sharpening device the tendency is to hold and force the sharpening device firmly in place upon the edge of the stationary cutter-blade, so that there will be no liability of its accidental displacement. The abrading-face of the sharpening device upper-

most will of course be of uniform thickness from end to end, so that the cutter-blades as they contact therewith will be uniformly ground from end to end and all of the revolving cutter-blades will be uniformly and evenly sharpened.

The unkerfed edge of the body *a* is also preferably formed with an abrading-surface. It will be apparent that the sharpening device, while specially adapted for application and use upon a lawn-mower, may at the same time be employed for a variety of other uses in the same manner as any ordinary hone or whetstone, so that the device may serve a wide range of uses, its special use being, as above described, for application to the stationary cutter-blade of a lawn-mower, it being only necessary then to revolve the revolving cutter-blades to effect their complete sharpening in a simple, efficient, and economical manner, the operation being so simple that any user of a lawn-mower can readily sharpen his own machine, making it unnecessary for him to take his machine to be ground.

It is well understood that the fixed lower cutter-blade *d*, while stationary in operation, is made adjustable. Its cutting edge may readily be tilted or dropped away from the revolving cutter-blade *e* a required distance in order to apply my improved sharpening device thereto for sharpening the revolving cutter-blades.

When the operation of sharpening has

been completed, the lower cutter-blade is simply adjusted again in a well-known manner into proper relation with the revolving cutter-blades.

What I claim as my invention is—

1. A sharpening device for sharpening cutter-blades of lawn-mowers and for other uses, comprising a body provided with an abrading-surface, and with an open kerf or slot in one edge thereof.

2. A sharpening device for sharpening cutter-blades of lawn-mowers and for other uses, comprising a body provided with an open longitudinally-extended kerf in one edge thereof, said body provided with abrading-surfaces on opposite sides of said kerf whereby the device is reversible for application for sharpening blades of lawn-mowers.

3. A sharpening device for sharpening the rotatable cutter-blades of a lawn-mower, said sharpening device comprising a single integral body provided with an abrading-surface, and with an open longitudinally-extended kerf or slot in one edge thereof to receive the fixed cutter-blade of the mower.

In testimony whereof I have signed this specification in the presence of two subscribing witnesses.

GEORGE H. PAULUS.
